United States Patent Office

Des. 187,837
Patented May 3, 1960

187,837

HEATER

Douglas W. Anderson, Palatine, Ill., assignor to The Siegler Corporation, Centralia, Ill., a corporation of Delaware

Application November 23, 1959, Serial No. 7,338

Term of patent 14 years

(Cl. D81—19)

Figure 1 is a perspective view of a heater, showing my new design;

Figure 2 is a plan view; and

Figure 3 is a side view thereof.

The back of the heater is substantially plain.

I claim:

The ornamental design for a heater, substantially as shown and described.
